No. 832,669.

PATENTED OCT. 9, 1906.

C. G. HAWLEY.
BRAKE BEAM.
APPLICATION FILED JULY 27, 1906.

UNITED STATES PATENT OFFICE

CHARLES GILBERT HAWLEY, OF CHICAGO, ILLINOIS.

BRAKE-BEAM.

No. 832,669.

Specification of Letters Patent.

Patented Oct. 9, 1906.

Application filed July 27, 1906. Serial No. 328,074.

To all whom it may concern:

Be it known that I, CHARLES GILBERT HAWLEY, a citizen of the United States, and a resident of Chicago, county of Cook, and State of Illinois, have invented a certain new, useful, and Improved Brake-Beam, of which the following is a full, clear, and exact description, such as will enable others skilled in the art to which it appertains to make and use the same.

My invention relates to improvements in brake-beams, and has special reference to improvements in brake-beams of that class known as "single-beam" brake-beams.

Single-member beams usually comprise a brake-shoe and a fulcrum bearing beam or member which is formed from a rolled shaped or flanged beam. Such brake-beams are strong and are favored by railroad operators by reason of their low cost. Some such beams are made from ordinary rolled I-beams. In such cases the compression and tension cords or portions of the beam are parallel. In other cases the compression cord of the beam is made straight and the tension cord or portion is bowed, this being done by forcing apart the flanges of the beam at the middle. A beam thus treated is greatly strengthened; but the spreading of the flanges involves much labor and the expenditure of great force.

The object of my invention is to provide a single-member brake-beam which may be manufactured at less cost than those above described.

To this end my invention consists in a brake-beam which is characterized by a straight compression member and a bowed or bent tension member united at their ends in such manner as to constitute a single integral member.

In carrying my invention into effect I employ two structural or rolled bars or beams, one straight and the other bowed, and unite the ends thereof by welding their web portions together, all as hereinafter described, and particularly pointed out in the claims.

My invention will be more readily understood by reference to the accompanying drawings, forming a part of this specification, and in which—

Figure I illustrates a brake-beam embodying my invention. Fig. II is a detail view illustrating the ends of the component members of the beam in readiness for welding. Fig. III is an enlarged cross-section of

the end of the beam on the line III III of Fig. I. Fig. IV illustrates a beam like unto that of Fig. I, but modified as to the manner of forming and joining the end web portions of the component parts. Fig. V is an enlarged section on the line V V of Fig. IV. Fig. VI illustrates a further modification of my invention, in which the webs of the two parts are lapped and welded. Fig. VII is an enlarged section on the line VII VII of Fig. VI. Fig. VIII is an enlarged section on the line VIII VIII of Fig. VI.

The beam illustrated in Figs. I, II, and III comprises two beams or members 2 and 3, which are T-shaped in cross-section. 2 is the compression member of the beam, and 3 the tension member, the latter being bent and making the beam deeper at the center than at the ends. In preparing the parts 2 and 3 I preferably provide them with enlarged web portions 2' 3' at the ends. These ends are placed in abutment and are then welded together in any suitable manner, as by means of an electric welding-machine. When the ends have been joined in this manner, the two parts 2 and 3 together constitute a single brake-beam member. The straight end portions of this member are equipped with brake-heads 4, and the middle of the beam is equipped with a strut 5 and a fulcrum-piece 6. The combination strut and fulcrum may be of any suitable form adapted to fit the portions or members 2 and 3. For the butt-weld of Fig. I, I may substitute the scarf-welds 6' 6', (illustrated in Figs. IV and V,) which quite as effectively unite the compression and tension members of the beam. Again, a beam composed of like members—viz., T-shaped beams 7 and 8 (see Fig. VI)—may be made by lapping the webs thereof at the ends and uniting the engaging surfaces of the webs by the process of welding. I prefer that the welded surfaces shall be limited to the straight portions of the members 7 and 8, as indicated by dotted lines 9 in Fig. VI. In manufacturing this beam I prefer to relatively offset the web ends of the members in order that the webs may occupy the same plane at the middle of the beam.

It will be evident that the straight compression member and the bent tension member may be of different forms in cross-section and generally that any two webbed or flanged members may be employed in making up my novel single beam. Many of these forms I have already developed; but of all I

prefer the substantially I-shaped beam herein illustrated. I do not, however, confine my invention thereto.

Having thus described my invention, I claim as new and desire to secure by Letters Patent—

1. In a brake-beam of the single-beam type, a beam proper comprising a T-shaped straight compression member and a bent tension member having its ends welded to the web ends of the compression member, substantially as described.
2. In a brake-beam of the single-beam type, T-shaped compression and tension members welded together at the ends and

spread apart at the middle, substantially as described.

3. In a brake-beam of the single-beam type, a straight flanged beam, in combination with a bent flanged beam, said beams being welded together at the ends and spread apart at the middle, substantially as described.

In testimony whereof I have hereunto set my hand, this 19th day of July, 1906, in the presence of two subscribing witnesses.

CHARLES GILBERT HAWLEY.
